UNITED STATES PATENT OFFICE

JEFFERSON M. PARRISH, OF RICHMOND, VIRGINIA

METHOD OF MIXING FERTILIZERS

Application filed November 10, 1926. Serial No. 147,578.

This invention relates to a method of and apparatus for mixing pulverized or powdered materials and particularly relates to the mixing of commercial fertilizers.

In the manufacture of commercial fertilizers it is usual to prepare large quantities of the several ingredient materials and to store them in a pulverized condition in bins or warehouses. The mixing of these materials preparatory to shipment in their salable form does not always occur immediately but most usually at a later date. Great care is taken during this time in the storage of the various materials to guard against the formation of lumps therein, but with all the care which may be taken some lumping always occurs, due to inherent qualities of some of the materials coupled with conditions that cannot easily or economically be avoided. For example, the materials known as acid phosphate and nitrate of soda readily form into lumps in the presence of even a small amount of moisture. It is customary, therefore, in the process of mixing fertilizers to include a screening operation, and sometimes also a crushing operation for the purpose of removing the lumps so that a homogeneous mixture of pulverized or fine materials may be obtained.

The methods heretofore practiced, so far as applicant is aware, have consisted in forming a batch of measured quantities of the several materials, raising it by a bucket or other hoist to an elevated bin, feeding from the bin to a screen, discarding or recrushing the tailings from the screen and finally mixing the fines which passed the screen into salable form. The final mixture was put into cars, bags or other containers as it came from the mixer, or was again taken up in elevators for this purpose.

In the one case, where the tailings from the screen were discarded, it was naturally impossible to obtain a proper mixture from the weighed materials. In the other case, where the tailings from the screen were returned to the batch, it was difficult to obtain proper crushing for the reason that the screen tailings contained lumps of widely varying sizes. This presented difficulties. A crush-

ing mill capable of accommodating the larger lumps would not readily crush the fine lumps and a mill well suited for crushing into fine sizes, i. e. completely pulverizing, would not readily accommodate the larger lumps.

This will be readily understood from an explanation of the difficulties encountered with the ball mill type of crusher, taken by way of example. When large lumps are to be crushed a ball mill having large spheres would be used in order to provide the necessary weight for crushing the big lumps. These large balls would obviously fail to touch more than a few of the smaller lumps and hence while well suited for rapid crushing of larger lumps would require a great deal of time for crushing all of the smaller lumps. Again, when small lumps are to be crushed smaller balls would be used and these small balls would be too light to crush large lumps, which would have to be discarded, thereby producing an improper mixture as in the first case where no crusher at all was used, though of course with a smaller degree of error.

Where the roller type of crusher is used and only a single crusher employed for both fine and coarse tailings, it must necessarily be set close to crush the material sufficiently fine. When large lumps of a material such as acid phosphate are passed through a small opening between rollers, they are highly compressed and instead of disintegrating into small particles they tend to become moist and form into flat sticky cakes which not only gum the crusher rollers but clog the openings of the screen.

According to the present invention, these and many other difficulties are overcome by a process which includes more than one screening or separating operation and a corresponding number of crushing operations and in which the crusher for each screen is peculiarly adapted to handle the material refused by its associated screen. By this process all of the lumps can be broken so that it will not be necessary, within the limits of time required for economical mixing, to discard any of the lumps, wherefore, it will be

seen that a thoroughly accurate mixture will be produced.

Apparatus for effecting the above mentioned and other beneficial results and in which certain features of novelty will be found, is disclosed in the accompanying drawings, in which:

Fig. 1 is a diagrammatic view principally in front elevation of one embodiment of apparatus for effecting this invention; and

Fig. 2 is a similar view of the apparatus as seen from the right of Fig. 1.

Referring to the drawings, in which like reference characters refer to like parts throughout the several views, the numeral 10 designates a conveyor or elevator which may be of the bucket type having buckets 11 carried by a chain 12 passing about drive pulleys in the usual way. The shaft 13 and 20 sprocket drive wheel 14 for the upper pulley appear in the drawings while the showing of the pulley at the lower end of the elevator is omitted.

The ingredients to be mixed may be 25 weighed according to the type of fertilizer to be prepared and deposited at the lower end of the conveyor accessible to the buckets. If desired, a hopper 10^a may be employed for this purpose together with a breaker for 30 crushing lumps which are too large to be handled by the buckets of the conveyor.

A chute 15 leads the material from the top of the conveyor to a primary separator or coarse screen 16 provided with a housing 35 17, drive shaft 18, and pulley 19. The fines from this screen pass into a hopper 20 while the tailings enter a chute 21. The tailings from the chute 21 enter a coarse crusher 22, from whence they emerge, after being 40 crushed, into a chute 23 leading into the side of the elevator 10. The coarse crusher 22 may be driven through a shaft 24 and pulley 25.

The fines which passed through the apertures of the screen 16 and dropped into hopper 20, flow by way of a chute 26 leading from the hopper into a secondary separator or very fine screen 27. As in the case of screen 16, the screen 27 is enclosed in a housing 28 and is provided with a shaft 29 and pulley 30. The fines from the screen 27 fall into a hopper 31 while the tailings enter a chute 32. The tailings from the chute 32 enter a fine crusher or pulverizer 33, from whence they 55 emerge, after being crushed, into a chute 34 leading into the side of the elevator 10.

The fines which passed through the apertures of the screen 27 and dropped into hopper 31, flow from the lower end of the hopper 31 into a feed hopper 35 of a mixer 36. The mixer is preferably large enough to receive an entire batch of mixture but the hopper 31 may be made large enough to hold a part or all of the batch and by providing 65 the lower end of chute 31 with a gate the

mixture held therein may be fed to the mixer as desired. This mixer may be supported on trunnions and be driven through gears 37, 38, a shaft 39 and a pulley 40. The mixer discharges its product by a spout 41 into a 70 sacking hopper 42.

In operation, a batch of fertilizer, composed of weighted amounts of the several ingredients is fed to the buckets at the lower end of the elevator. This unmixed and partially lumpy batch is raised by the elevator and fed into the coarse screen 16 by way of chute 15. The screen 16 removes the large lumps as tailings which are fed into the coarse crusher 22 by chute 21. The crusher 75 breaks the large lumps into smaller ones, (no attempt being made to pulverize at this point) and feeds them back into the batch by way of chute 23. The conveyor takes them again to screen 16 with the body of the batch. The fines from screen 16 pass into hopper 20, chute 26 and then into the fine screen 27. The tailings from this screen 80 pass thru chute 32 to the fine-crusher or pulverizer 33. The pulverized material is 85 fed by chute 34 back into the conveyor where it is elevated and passed to screen 16 as before. The material which would not originally pass screen 27 is broken sufficiently by the coarse-crusher 22 and pulverizer 33 to 90 cause it to do so when it is returned thereto, and within a short time the entire batch will 95 have passed the screen 33 as fines. When the mixer 36 has received the entire batch from hopper 31 and feed hopper 35, it is started 100 into operation to stir the several pulverized ingredients into a homogeneous mass. The spout 41 of the mixer is under the control of an operator and when the batch has been thoroughly mixed it is passed by spout 41 105 into the sacking hopper 42 where it may be sacked, loaded directly into cars, or disposed of in any other desired manner.

It will thus be seen that according to the above described invention a noteworthy improvement in the method of mixing and conditioning fertilizers or other pulverized materials has been effected. By the provision and judicious combination of a plurality of graded screens and a plurality of associated 110 graded crushers, beneficial results are produced which could not have been predicated upon a mere duplication of existing apparatus.

While the embodiment illustrated and described is that which is at present preferred, it will be understood that various other embodiments are contemplated as falling within the scope of the appended claim.

Having thus described the invention, what 115 is claimed as new and desired to be secured by Letters Patent is:

In a fertilizer mixer, the combination with an elevator and means for delivering the materials to be mixed to the elevator, of 120

a coarse screen receiving the materials from the elevator, a coarse crusher receiving the tailings from the coarse screen and delivering the crushed materials to the elevator, a fine screen receiving the fines from the 5 coarse screen, a fine crusher receiving the tailings from the fine screen and delivering the finely crushed materials to the elevator, and a mixer receiving the fines from the fine screen whereby the large and small 10 lumps in the original mass of materials are separately crushed and the operation repeated until all of the batch is suitably pulverized and delivered to the mixer.

15 In testimony whereof I hereunto affix my signature.

JEFFERSON M. PARRISH.
